UNITED STATES PATENT OFFICE.

LOUIS JOSEPH KOCH AND GEORGE WALTER KOCH, OF EVANSVILLE, INDIANA.

DOOR-HOOD.

No. 910,393.

Specification of Letters Patent.

Patented Jan. 19, 1909.

Application filed July 2, 1908. Serial No. 441,563.

To all whom it may concern:

Be it known that we, LOUIS JOSEPH KOCH and GEORGE WALTER KOCH, citizens of the United States, residing at Evansville, in the 5 county of Vanderburg and State of Indiana, have invented certain new and useful Improvements in Door-Hoods, of which the following is a specification.

Our invention relates to hoods for shading 10 doors and windows and protecting door steps from rain and snow and has for its object the provision of a hood in which the roof portion is formed of a single plate of sheet metal having one edge turned up at an obtuse angle to 15 the surface of the roof to be secured to the lintel of the door, its opposite edge turned downwardly and then curled upwardly to form a gutter, and the side edges bent upwardly at right angles to the roof and then back on 20 itself and extended below the level of the roof to stiffen the roof and at the same time form a watershed to prevent the rain water from running over the side edges of the roof.

The construction of our improved door hood 25 will be described in detail hereinafter and illustrated in the accompanying drawings in which—

Figure 1 is a view of a fragment of a door showing our improved hood in position, Fig. 30 2, a longitudinal sectional view of the roof portion, and Fig. 3, a cross section of one side edge of the roof portion.

In the drawings similar reference characters indicate corresponding parts in all of the 35 views.

A indicates a door having the lintel B and the posts C.

Our improved hood consists of a roof portion 1 made of a single plate of sheet metal 40 having one edge bent upwardly at an obtuse angle as shown at 2 to be secured to the lintel B by means of nails or screws 3. When secured in position as shown in Fig. 1 the roof has a pitch away from the door as shown and 45 is braced in this position by means of brace rods 4 riveted or otherwise secured to the sides of the roof 1 adjacent to its lower end, and secured to the door posts C.

The lower edge of the roof 1 is turned down- 50 wardly as shown at 5 and then bent back on

itself to form a gutter 6 to carry off the water to one side or the other of the roof.

The two side edges of the roof portion 1 are bent upwardly at right angles to the roof portion 1 as shown at 7, then back on itself as 55 shown at 8 and has its edge extending below the lower surface of the roof and formed with scallops 9 or other design to add to the appearance of the device. The upwardly extending portion 7 forms a watershed to prevent the water from running over the sides of roof portion 1 as well as stiffening ribs to hold 60 the roof in a flat position.

It will be understood that our improved hood is assembled ready to be attached to the 65 door or window which may be accomplished in a very short time and that by turning the four edges of the roof portion 1 as described it is stiffened so as to prevent it from bending or buckling either before or after being secured 70 in position.

Having thus described our invention what we claim is—

1. As an article of manufacture, a door hood comprising a plate of sheet metal having one 75 edge bent upwardly at an obtuse angle, the opposite edge bent downwardly and then back on itself forming a gutter, the side edges bent at right angles to the roof portion, and brace rods secured to the roof portion. 80

2. As an article of manufacture, a door hood comprising a flat plate of sheet metal having one edge bent upwardly at an obtuse angle thereto to be secured to the lintel of a door, its opposite edge bent downwardly and back 85 on itself to form a gutter, the side edges bent upwardly at right angles to the roof and then backwardly forming stiffening ribs and watersheds, and the free edges extended below the level of the roof portion and decoratively cut, and brace rods secured adjacent to the lower corners of the roof portion and adapted to be secured to the side posts of a door. 90

In testimony whereof we hereto affix our signatures in the presence of two witnesses. 95

LOUIS JOSEPH KOCH.
GEORGE WALTER KOCH.
